UNITED STATES PATENT OFFICE.

CHARLES E. DATH, OF CHICAGO, ILLINOIS, ASSIGNOR TO WILLIAM H. MINER, OF CHAZY, NEW YORK.

DRAFT-ARM FOR RAILWAY-CARS.

1,193,364.

Specification of Letters Patent.

Patented Aug. 1, 1916.

Application filed November 30, 1914. Serial No. 874,654.

To all whom it may concern:

Be it known that I, CHARLES E. DATH, a citizen of the United States, residing at Chicago, in the county of Cook and State of Illinois, have invented a certain new and useful Improvement in Draft-Arms for Railway-Cars, of which the following is a full, clear, concise, and exact description, reference being had to the accompanying drawings, forming a part of this specification.

This invention relates to improvements in draft arms for railway cars.

An object of the invention is to provide a draft arm for railway cars so constructed that a draft rigging employing coupler connecting key and supporting keys may be readily attached to and detached therefrom.

The invention furthermore consists in the improvements in the parts and devices and in the novel combinations of the parts and devices, as herein shown, described or claimed.

In the drawing forming a part of this specification, Figure 1 is a central longitudinal vertical section of a portion of a car underframe, showing my improvements in connection therewith. Fig. 2 is an enlarged sectional view taken substantially on the line 2—2 of Fig. 1 and Figs. 3 and 4 are vertical sectional views taken substantially on lines 3—3 and 4—4 respectively of Fig. 1.

In said drawing, 10—10 denote wooden center sills of a car underframe; 11 an end sill; 12 the end or buffer block; 13 the floor; 14 a body bolster; 15 sub sills and 16 a bracing angle iron interposed between the rear side of the body bolster and the adjacent ends of the sub sills 15.

Secured to the under sides of the sills 10—10 are draft arms A A, each of which consists of an elongated casting of generally T shape in cross section and having an upper wide horizontal flange 17 and vertical web 18, the inner portion of which horizontal flange 17 is suitably connected to the center sills as by vertical sill bolts 19—19 and the outer sides of the flanges 17 are riveted to the lower flanges 20 of channel beams 21 secured to the outer sides of the sills 10. As

clearly shown in Fig. 1, each draft arm A is recessed at its front end, as indicated at 22, so as to extend beneath the buffer block 12 and each draft arm is furthermore extended rearwardly so that the rear end engages the body bolster, as indicated at 23. Each draft arm is also provided with three elongated slots 24, 25 and 26, each slot being surrounded by a flange 27 to thereby strengthen the castings and also to give a wide bearing for the keys hereinafter described. To further strengthen the casting, intermediate connecting horizontal ribs 28 are provided between the outstanding flanges 27 and also a rib 29 extending from the rear of the slot 26 up to the top of the casting.

The draft rigging which I have shown, comprises a draw bar 30, front follower 31, rear follower 32, combined friction cylinder and spring casing 33, friction devices 34, 70 coupler, key 35, front supporting key 36, which passes through the slotted front follower 31, rear supporting key 37, and a substantially cylindrical casing 38 in which the followers, shell and friction devices are enclosed and supported, said casing 38 being also provided with suitable, elongated slots for each of the keys 35, 36 and 37. As will be understood, the case 38 is open at either end to permit the insertion of the followers, 80 spring, etc., therewithin.

At their front ends, the channels 21—21 may be additionally secured to the center sills and end sill by angle irons 39. (See Fig. 3). 85

I claim:

1. In an under-frame for railway cars, the combination with wooden center sills having channel beams secured to the outer sides thereof, of draft arms, each draft arm 90 having a horizontal upper flange secured to the underside of a sill and the lower flange of a channel, each draft arm having also a vertical web provided with elongated slots therein.

2. In a structure of the character described, the combination with wood center sills having reinforcing plates secured to the outer sides thereof, each of said plates being provided at its lower end with an out- 100

turned flange, of draft arms, each draft arm having a horizontal upper flange and a vertical web depending therefrom, said draft arms being secured to said sills and flanges of the reinforcing plates by securing devices passing through the horizontal flanges of the draft arms, said draft arms being each

provided with means by which a draft gear may be secured thereto.

CHARLES E. DATH.
